(57) CLAIM

The ornamental design for a griddle scraper, as shown and described.

DESCRIPTION

FIG. 1 is a top view of a griddle scraper showing my new design;

FIG. 2 is a bottom view thereof;

FIG. 3 is a rear view thereof;

FIG. 4 is a front view thereof;

FIG. 5 is a side view thereof; and,

FIG. 6 is a perspective view thereof.

The side not illustrated is a mirror image of the side illustrated in FIG. 5 and the shackle, wing nuts and structure on the underside of the handle illustrated in dashed lines do not form part of the claimed design.
